O. J. CABLE

CONCRETE WALL ERECTION FORM AND FORM CLAMP

Filed Feb. 26, 1924

INVENTOR:
OSWALD JOSEPH CABLE
BY: Francis E. Boyce
ATTORNEY

UNITED STATES PATENT OFFICE.

OSWALD JOSEPH CABLE, OF NEWTOWN, NEAR SYDNEY, NEW SOUTH WALES,
AUSTRALIA.

CONCRETE-WALL ERECTION FORM AND FORM CLAMP.

Application filed February 26, 1924, Serial No. 695,170, and in Australia April 3, 1923.

Hitherto in the erection of concrete walls the forms have been erected between a supporting timber frame at each side of the mould which latter has been built up of sections or forms held apart the requisite width of wall by hollow distance pieces such as piping and held or tied together against lateral displacement by bolts through such pieces and orifices in the wall 5 of the forms or by wires threaded through such pieces and orifices, and secured to the supporting frame by said wires or by wires threaded through other orifices in the frame walls and nailed to or twisted around convenient members of the supporting frame which method has been slow and costly.

This invention has been specially devised in order to cheapen, simplify and expedite the erection of concrete walls and comprises 20 an improved wall form, an improved method or manner of erecting the forms to form a mould for the wall to be cast therein and supporting the forms without external or independent supporting frames as hitherto 25 used thereby dispensing with same and the cost thereof and the time and cost in erecting and removing it, a specially designed and functioning distance and tie member, and an improved clamp for tightening and 30 holding together the erected forms and studs.

The improved method of erecting the forms consists in positioning them edgewise in superimposed tiers upon each side of a 35 vertical stud and pinning and clamping the whole together to form each of parallel sides of a mould and in distancing and tying the parallel walls with the distance and tie member positioned between the tiers 40 across the cavity and with each end pinned to the horizontal rails of the forms.

The improved wall form is constructed of timber preferably light and consists of a rectangular frame say of the timber 3 45 inches by 2 inches secured at meeting ends and with intermediate rails and upon one face of said frame are affixed face boards (which may be tongued and grooved along their meeting edges) thus providing a form 50 with one face flush to be the inside face and upon the other face outstanding members or rails of the frame which members are coincidently orificed so that a locking pin

may be passed through the meeting horizontal members in edgewise superimposed courses of forms and the leg of a clamp may be passed through the vertically disposed end members and a complementarily orificed stud positioned therebetween. If desired the forms may have in the external 60 faces of the edges to be disposed horizontally in erection a shallow transverse recess about the pin holes through the rails to receive the tie members and allow the frames to meet.

The improved clamp constructed preferably of one piece of round iron of requisite diameter, strength and length and galvanized or otherwise protected is of rectangular or oblong form and open at one end by 70 one side member being shorter than the other and said other side having an end member turned to a right angle therewith and to an angle of say forty five to sixty degrees from the plane thereof so that the 75 short member may be passed through the vertical rails of the forms and the then middle stud until the closed end embraces the vertical rail of one form and the angled end of the other side will swing or may be 80 swung inwardly so as to embrace the vertical member of the other form when a wedge is driven down between said angled end and the rail thus tightly clamping the forms 85 and stud together and holding them against lateral and/or longitudinal displacement.

A distance and tie member consists of a 90 flat slat preferably of metal of requisite strength, width and length according to the required width of wall to be cast and having therein near each end a locking pin orifice and preferably having each end turned at about a right angle.

And in order that the invention and a practical application of the same may be 95 readily understood the same will now be described with reference to the accompanying drawings in which:—

Figure 1 is an external elevation of assembled forms,

Figure 2 is a transverse sectional elevation on the line 2—2 in Figure 1 of parallel forms with the distance and tie members pinned in position and distancing and tying them and showing the tightening wedges in 105 the clamps,

Figure 3 is an external elevation of a form showing the intermediate rails,

Figure 4 is a plan of the same,

Figure 5 is a vertical sectional elevation on the line 5—5 in Figure 3,

Figure 6 is a plan of the clamp,

Figure 7 is an end elevation of the same showing the angled end, and

Figure 8 is a perspective of the tie member.

The improved form is constructed of timber, preferably light, and consists of a rectangular frame of side rails 7 and end and intermediate rails 8 with face boards 9 affixed upon one face to form a flush "inner" face having locking pin orifices 10 therethrough the side rails 7 and intermediate rails 8 and the end rails 8 having clamp leg orifices 11 therethrough. Said forms are conveniently constructed to an external size of 6 feet by 2 feet and the intermediate rails 8 are spaced 2 feet so that a frame may be used on end and said rails will be coincident with the side rails of frames on their sides in the opposite side wall of the mould.

In the edge face of one or both the rails 7 which will be disposed horizontally in erection transverse recesses may be formed about the locking pin orifices to receive the tie members so that superimposed frames may meet and make a tight joint.

When convenient the frames may be positioned vertically and slots 21 are made through the face boards alongside the intermediate rails to permit of a tie member being passed therethrough and locked to said rail by a pin passed through the orificed end of the tie and said rail.

The distance and tie member 12 of suitable metal such as galvanized iron of requisite strength, length and width has locking pin orifices 13 therethrough near each end and requisite distanced and preferably has each end angled as at 14.

The clamp for holding and tightening the meeting vertical ends of the forms together are preferably constructed of round iron in one piece formed to provide parallel side members 15 and 16 and one end 17 in the same plane and one side member 15 being shorter than the other 16 which has an end piece 18 angled to about sixty degrees from the plane of the side members thus leaving one end open to permit of the short member 15 being passed through the orifices in the form rails and an embraced stud and the clamp being turned against the forms so that the end 18 will embrace one of the end rails 8 when a wedge 19 is driven between said end 18 and the end rail 8 causing the closed or opposite end 7 of the clamp to grip the rail 8 of the next form and locking and clamping said forms and the stud tightly together.

In erecting the forms to form a cavity

mould for the wall to be cast therein parallel forms with flush faces towards each other are placed upon edge in tiers of courses at each side of a supporting and stiffening vertical stud 20 preferably the full height of the wall to be cast, tie members 12 are laid upon the top edges of each course of forms transversely of the cavity and with their orifices 13 coincident with the orifices 10 in the top side or then horizontal upper rail of said forms the turned down or angled ends of said tie members embracing said rail and holding said members in position and preventing outward lateral displacement of the forms. When the next course of forms has been superimposed locking pins or passed through the bottom side rails 7 thereof the tie member and the top side rails of the lower forms and so lock the whole together, the tie members being of sufficient strength to hold the parallel forms apart the requisite width and being secured between and across said forms prevent lateral displacement thereof and hold or stiffen the erected forms or mould in correct position during casting of the wall.

The clamps are then applied to the vertical or end rails 8 of the forms and the studs 20 by passing the short leg 15 of the clamp through the coincident orifices turning the angled end 18 of the clamp in against the forms until it embraces one of the rails 8 when a wedge 19 is driven between said end 18 and the rail 8 so clamping the forms and stud together and making a tight joint.

After casting and setting of the wall the mould is disrupted as well understood and the ends of the tie members projecting from each side of the wall are fractured off.

I claim:—

1. A concrete wall erecting form, comprising sectional frames each having face boards on one side thereof adapted to form a flush face when assembled, the vertical members of the frames being provided with apertures therethrough, the apertures of one frame being adapted to align with the apertures of a longitudinally spaced frame for the reception of clamping members for releasably securing together the vertical members of frames abutting a vertical stud having coincident apertures and interposed between vertical members of said frames, and the horizontal members of said frames having exposed recesses in abutting faces to receive the ends of tie members interposed between said members and having coincident apertures for the reception of means for releasably securing together said tie members and the horizontal members of abutting frames and maintaining said frames in vertical alignment.

2. An open-ended clamp of rectangular formation for concrete wall erecting forms, said clamp having a short leg, one end and

a longer leg in the same plane and an end integral with said longer leg and extending at an angle to the plane thereof.

3. A concrete wall mould comprising sectional forms having vertical and horizontal frame members, said forms being spaced longitudinally and superposed and each having coincident apertures in the vertical frame members and in the horizontal abutting frame members thereof, pins through the apertures of the abutting horizontal frame members to maintain the moulds in vertical alinement, vertical studs having apertures coincident with the apertures in the vertical frame members of the forms interposed between said members, and clamping means through said frames and studs to secure them against longitudinal displacement.

20 4. A concrete wall mould comprising a pair of spaced parallel tiers of sectional forms having vertical and horizontal frame

members each of said forms having coincident apertures in the vertical frame members, transverse open recesses in the top horizontal frame member, and coincident apertures in each top and bottom frame member, tie members having an aperture in each end interposed at each end between superposed forms in each spaced tier with the aperture coincident with the apertures of said top and bottom frame members, pins through said frame members and tie member ends, vertical studs having apertures coincident with the apertures in the vertical frame members of the forms interposed between said members, and clamping means through said members and studs to secure them together and against longitudinal displacement.

Dated the twenty ninth day of January, one thousand nine hundred and twenty-four.

OSWALD JOSEPH CABLE.
